Specification for Design. **Patented Dec. 14, 1915.**

Application filed February 9, 1915. Serial No. 7,127. Term of patent 14 years.

To all whom it may concern:

Be it known that I, JACOB C. McCALL, a citizen of the United States, residing at Fort Worth, in the county of Tarrant and State of Texas, have invented a certain new, original, and ornamental Design for Search-Lights, of which the following is a specification, reference being had to the accompanying drawings, forming part thereof, in which—

Figure 1 is a side elevational view of a search light showing my new design, and Fig. 2 is a front elevational view thereof.

I claim:—

The ornamental design for a search light, as shown.

In testimony whereof I have signed my name to this specification in the presence of two subscribing witnesses.

JACOB C. McCALL.
